UNITED STATES PATENT OFFICE

137,735

DESIGN FOR A LOW TEMPERATURE CABINET

William S. Connell, Norwood Park Township,
Cook County, Ill.

Application September 3, 1943, Serial No. 111,055

Term of patent 7 years

(Cl. D67—3)

To all whom it may concern:

Be it known that I, William S. Connell, a citizen of the United States, residing at Norwood Park Township, in the county of Cook and State of Illinois, have invented a new, original, and ornamental Design for a Low Temperature Cabinet, of which the following is a specification, reference being had to the accompanying drawing, forming a part thereof.

I claim:

The ornamental design for a low temperature cabinet, as shown.

WILLIAM S. CONNELL.
